FISHING ROD HOLDER

Robert D. Miller, 5828 Ridgeway St.,
Peninsula, Ohio 44264

Filed Oct. 13, 1972, Ser. No. 299,955

Term of patent 14 years

Int. Cl. D22—05

U.S. Cl. D22—22

FIG. 1

FIG. 2

FIG. 3

FIG. 4

FIG. 5

FIG. 6

FIG. 1 is a top plan of the fishing rod holder;

FIG. 2 is a side elevation of the holder and its positionning bracket or support;

FIG. 3 is a left side elevation of the holder of FIG. 2;

FIG. 4 is a right side elevation of the holder of FIG. 2;

FIG. 5 is a bottom plan of the holder of FIG. 2; and

FIG. 6 is an exploded elevational view of the holder of FIG. 1 shown in reverse position and indicating the movement of the relative components of the holder.

I claim:

The ornamental design for a fishing rod holder, as shown.
